ABSTRACT OF THE DISCLOSURE

The invention comprises a tubular folder designed for containing books and the like during shipment. The ends of the folder may be closed by end panels hinged to the ends of one main panel. The other main panel as well as the side walls, extend beyond the ends of said one main panel, and the structure at each end of the folder is cut and creased to provide a partial end panel, and a projecting channel-shaped extension on each side of the partial end panel. The outwardly projecting channel-shaped extensions protect the contents from damage.

This invention relates to an improvement in book folders and deals particularly with a folder capable of protecting books or similar objects, and which may be made at relatively low cost.

Books such as law books and the like are normally packaged in folders of one type or another, usually made of corrugated paperboard. Certain of these containers, such as shown in my previous Patent 3,302,852 issued Feb. 7, 1967, are containers having recessed ends which support the ends of the book in spaced relation to the ends of the enclosing container. Such containers have been produced in high volume. However, I have found that extremely good results may be obtained at a somewhat lower cost, by providing a container in which the opposite side portions of the ends project beyond the center portion thereof, providing a container having channel-shaped projections at each end which serve to protect the ends of the book or similar article.

In most of the previous recessed end containers, the ends of the top and bottom panels of the container are provided with a first flap or flange connected to each end of each main panel and which is folded through substantially 180° to lie flat against the inner surface thereof. An end wall panel is hinged to each such liner flange to form the recessed container end. The resultant blank is thus longer than the main panels of the container by twice the length of the liner panels and twice the length of the end wall panels. An advantage of the present construction lies in the fact that the blank may be substantially decreased in size while still providing adequate protection for the contents.

A feature of the present invention resides in the provision of a container secured in tubular form and including a pair of main panels, substantially equal in width to the book and an intermediate pair of side wall panels which are equal in width to the thickness of the book being enclosed. One of the main panels is substantially equal in length to the book, and is foldably connected to a pair of end closure panels designed to fold over to close the ends of the tubular structure. The other main panel is somewhat longer than the length of the book. Partial end wall panels are foldably connected to the center portions of the ends of this main panel and are designed for folding outwardly of the end panels of the other main panels. Each partial end wall is hinged to a generally U-shaped reinforcing panel, the cross member of which is designed to be adhered in face contact with the first main panel. Flaps are hinged to the sides of

2

the reinforcing panel and are folded over the ends of the side walls and are adhered thereto. This results in a container having a substantially channel-shaped projection on each side of each end, these channel shaped projections on each side of each ends, these channel shaped projections acting to protect the ends of the enclosed book.

These and other objects and novel features of the present invention will be more clearly and fully set forth in the following specification and claims.

10 In the drawings forming a part of the specification, FIGURE 1 is a perspective view of the closed container.

15 FIGURE 2 is a diagrammatic view of the blank in flat folded form.

FIGURE 3 is a perspective view of one end of the container in partially closed position.

18 FIGURE 4 is a vertical sectional view through the end of the container in closed condition thereof.

20 FIGURE 5 is a diagrammatic view of the blank from which the container is formed.

The book folder is indicated in general by the letter A. The folder includes a main panel 10, a side wall panel 11, a second main panel 12, and a second side wall panel 13 connected along parallel fold lines 14, 15, and 16. The four panels are connected in tubular relation by suitable means such as by the tape strip 17. When in this condition, the blank appears as indicated in FIGURE 2 of the drawings.

22 The main panel 10 is connected to end closure flaps 20 along parallel fold lines 19, which intersect the previously described fold lines at right angles. The fold lines 19 are spaced apart a distance substantially equal to the length of the book being contained and the end panels 20 are proper size to close the ends of the tubular arranged walls which have been described.

24 The second main panel 12, as well as the first and second side walls 11 and 13 are of equal length and are somewhat longer than the main panel 10, the side walls 11 and 13 terminating along aligned cut lines 21 which extend across the side walls 11 and 13 and extend into the main panel 12 to terminate in widely spaced relation. Right angular cut lines 22 communicate with the inner opposed ends of the cut lines 21 and extend toward one another into the main panel 12. Fold lines 23 which are generally aligned with the fold lines 19 of the main panel 10 connect the inner ends of the cut lines 22 to connect the center portions of the main panel 12 to a pair of partial end wall panels 24. Cut lines 25 which are aligned with the cut lines 22 form an extension of the cut lines 22, and the other ends of the cut lines 25 are connected by parallel fold lines 26 which form edges of the partial end walls 24. In other words, the partial end walls 24 are defined by parallel fold lines 23 and 26, and by the cut lines 22, 25, on each side of each panel 24.

26 This arrangement provides a generally U-shaped flange 27 at each end of the main panel 12. Flaps 29 and 30 are hinged to opposite sides of U-shaped flanges 27 along parallel fold lines 31 which are generally aligned with, but somewhat outwardly offset from, the fold lines 15 and 16 defining the sides of the main panel 12.

28 In use, the carton A is erected into tubular relation with the main panels 10 and 12 in parallel relation and with the side walls 11 and 13 in parallel relation and in right angular relation to the main panels. The book or other such object is inserted into the tubular folder, and the closure flaps 20 are folded into right angular relation to the main panel 10 to close the ends of the tubular structure. The partial end walls 24 are next folded upwardly into face contact with the outer surfaces of the end panels 20. During this operation, the U-shaped flanges

27 are folded along the fold lines 26 so that the cross member of the U-shaped flanges 27, or the portion of each U-shaped flange 27 which extends beyond the fold line 26 is in overlapping relation with the end portions of the main panel 10 as indicated in FIGURE 1 of the drawings. The corner flaps 29 and 30 are folded to overlie the ends of the side walls 11 and 13, respectively, and are adhere thereto. A portion of each U-shaped flange 27 which overlaps the main panel 10 may also be adhered in face contact therewith.

When closed, the container appears as indicated in FIGURE 1 of the drawings, there being a channel-shaped projection on each side of each end of the container which projects beyond the end walls to serve as a protection for the ends of the book.

It will be noted that the channel-shaped projections at each corner of the folder are of double thickness along the sides of the folder, making the extensions very resistant to crushing or bending if the folder is dropped. Thus, while the blank which forms the folder is of somewhat smaller size than the recessed end folders previously made, the folder has been found to adequately protect the contents during shipment.

To facilitate the opening of the folder, parallel weakened lines of separation 32 extends across the blank from end to end thereof, the weakened lines preferably extending in right angular relation to the flutes of the corrugated paperboard. A generally H-shaped cut 33 in the main panel 10 intersects the weakened lines of separation and forms tabs 34 which may be grasped and pulled to tear the paperboard along the weakened lines of separation.

I claim:

1. A book folder including:

first and second main panels marginally connected in parallel relation by parallel side wall panels to provide a tubular body,

an end closure panel hinged to an end of said first main panel and foldable to close an end of said tubular body,

a partial end wall hinged to the center portion of said second main panel and spaced from said side walls, a U-shaped reinforcing flange including end portions and a cross connecting member having its cross connecting member hingedly connected to said partial end wall along a line of fold parallel to the hinge connection between said partial end wall and said second main panel and between the end portions of said reinforcing flange,

said cross connecting member being foldable into face contact with said first main panel whereupon said end portions thereof project beyond said partial end walls.

2. The structure of claim 1 and including side flaps on said end portions of said reinforcing flange foldable into face contact with the ends of said side walls.

3. The structure of claim 1 and in which the end portions of said reinforcing flaps, the ends of said side walls,

and the portions of said second main panel outwardly of said partial end panel form opposed channel-shaped extensions when secured together.

4. The book container comprising:

a tubular folder enclosing the book including a pair of main panels overlying opposite surfaces of said book and side panels connecting opposed edges of said book, end closure panels hinged to one of said main panels and folded across the ends of said tubular folder, and opposed channel-shaped projections on opposite sides of said main panels projecting beyond said end closure panels.

5. The structure of claim 4 and in which said channel-shaped projections include side wall portions of double thickness.

6. A blank for forming a book folder including: a first main panel, a first side wall panel, a second main panel and a second side wall panel connected along parallel fold lines, said panels being foldable to provide a hollow rectangular tubular sleeve, one of said main panels including a pair of end wall closure panels foldably connected to the ends thereof, the other of said main panels as well as said side walls extending beyond the lines of fold connecting said one main panel to said end wall closure panels, said blank including cut lines defining the ends of said side walls and extending into said other main panel to terminate in widely spaced relation, parallel cut lines intersecting the ends of said cut lines at right angles thereto and extending in opposite directions therefrom to define the ends of a partial end wall,

fold lines connecting the ends of said right angularly extending cut lines and defining the sides of said partial end wall,

the portions of said blank outwardly of the outermost of said fold lines, together with the portions of said blank outwardly of said cut lines defining a U-shaped flange foldable into overlapping relation to said one main panel,

7. The structure of claim 6 and including fold lines extending across said U-shaped flange generally aligned with the lines of fold connecting other main panel to said side wall panels to provide side flaps hinged to said U-shaped flange.
